Primary Examiner—Holly H. Baynham*Assistant Examiner*—Cynthia M. Chin(74) *Attorney, Agent, or Firm*—Cook, Alex, McFarron, Manzo, Cummings & Mehler, Ltd.(57) **CLAIM**

The ornamental design for a paddle wheel boat, as shown and described.

DESCRIPTION

FIG. 1 is a front perspective view of the design of the present invention.

FIG. 2 is a left side view of the design shown in FIG. 1.

FIG. 3 is a front view of the design shown in FIG. 1.

FIG. 4 is a rear view of the design shown in FIG. 1.

FIG. 5 is a top plan view of the design shown in FIG. 1; and,

FIG. 6 is a bottom view of the design shown in FIG. 1.
